UNITED STATES PATENT OFFICE.

OLIVER C. HALDEMAN AND JOHN R. HALDEMAN, OF KANSAS CITY, MISSOURI, ASSIGNORS TO THE HALDEMAN PORCELAIN CROWN COMPANY, OF KANSAS CITY, MISSOURI.

ARTIFICIAL DENTURE.

SPECIFICATION forming part of Letters Patent No. 764,528, dated July 5, 1904.

Application filed April 6, 1903. Serial No. 151,272. (No model.)

To all whom it may concern:

Be it known that we, OLIVER C. HALDEMAN and JOHN R. HALDEMAN, citizens of the United States, residing at Kansas City, in the county 5 of Jackson and State of Missouri, have invented certain new and useful Improvements in Artificial Dentures, of which the following is a specification.

Our invention relates to improvements in 10 dentistry; and it consists in the peculiar manner in which artificial crowns are secured to natural roots.

One of the objects of the invention is to provide a post which is separable from the crown, 15 so the latter may be ground and otherwise manipulated in fitting it to the exposed end of the root.

A further object is to construct the lower 20 end of the post in such a way that while it may be reliably secured to the crown the cavity in the latter to receive it will be comparatively small, and consequently will not materially affect the strength of the crown.

In the accompanying drawings, which illustrate the invention, Figure 1 shows an enlarged vertical section of a root and crown, which latter is secured to the former by our improved post. Fig. 2 is an enlarged vertical section of a crown, showing the peculiar 25 shape of the cavity arranged therein to receive the post. Fig. 3 is an enlarged detail perspective view of our improved post and key employed in securing the crown to the root. Fig. 4 shows a modified form of the crown 30 and post.

In carrying out our invention we employ a crown 1, composed of porcelain or other suitable material and provided with a peculiar-shaped cavity 2, which is enlarged at its open 40 end 3, is reduced at its inner end 4, and has a communicating angular portion 5, which of course does not have to extend toward the front surface of the tooth, as shown, but may extend in any other direction.

45 After the upper surface 6 of the crown has been ground to accurately fit the exposed terminal of root 7 the crown is furnished with the improved anchor 8, which tapers toward

its upper end 9, has a reduced lower terminal 10, adapted to snugly fit into the reduced 50 end 4 of cavity 2, and is provided with a lug 11 for engaging the angular portion 5 of the cavity.

After the lower end of the post has been inserted in cavity 2 it is removably locked therein by a key 12, which is slipped down between the wall of the enlarged portion of the cavity and that side of the post opposite from the angular lug 11, as shown in Fig. 1. By withdrawing said key the post may be readily detached from the crown by disengaging the lug from the angular portion of the cavity.

In addition to locking the post in position in the crown the key also reinforces it at joint 13 between the root and crown, so that mastication of food is not liable to bend said post and loosen the crown from the root.

There is an occasional demand on the trade for a crown provided with a filling. We meet this demand by extending the reduced portion 4 of the opening through to a depression 4^a in the wall of the crown, which is plugged with a filling 14, secured to the terminal of an elongated reduced portion 10^a of the anchor, as shown in Fig. 4.

75 From the above description it is apparent that we have produced an anchor which is simple in form, inexpensive to manufacture, and thoroughly reliable for the purpose intended.

Having thus described our invention, what 80 we claim, and desire to secure by Letters Patent, is—

1. A crown provided with a rectangular cavity having a reduced terminal and an undercut angular portion communicating with one 85 side thereof, a rectangular post having a reduced end adapted to enter the reduced terminal of the cavity, and a lug formed on the post near its reduced end adapted to enter the undercut angular portion in the crown, and 90 a key for detachably locking the post in the crown.

2. A crown provided with a cavity having an undercut portion communicating therewith, a post adapted to fit into the cavity, a lug 95 on the post adapted to fit into the undercut

portion of the cavity, and a key for removably locking the post in the crown.

3. A crown having an enlarged opening, an angular portion communicating therewith, 5 and a reduced portion which communicates with a depression in the wall of the crown; a post, a lug formed integral therewith and adapted to fit into the angular portion of the crown, a reduced portion on the post adapted 10 to fit into the reduced portion of the opening in the crown, a filling on the end of said re-

duced portion adapted to fill the depression in the wall of the crown, and a key for removably locking the post in the crown.

In testimony whereof we affix our signatures 15 in the presence of two witnesses.

OLIVER C. HALDEMAN.
JOHN R. HALDEMAN.
